UNITED STATES PATENT OFFICE.

ANDREW SPORUP, OF EUREKA, CALIFORNIA.

AUTOMATICALLY-ADJUSTABLE WRENCH.

1,305,571.

Specification of Letters Patent. Patented June 3, 1919.

Application filed April 11, 1918. Serial No. 227,938.

To all whom it may concern:

Be it known that I, ANDREW SPORUP, a citizen of the United States, residing at Eureka, in the county of Humboldt and 5 State of California, have invented certain new and useful Improvements in Automatically-Adjustable Wrenches; and I do declare the following to be a full, clear, and exact description of the invention, such as will 10 enable others skilled in the art to which it appertains to make and use the same.

This invention relates to wrenches, and it relates more particularly to an automatically adjustable wrench for turning either cylindrical or prismatic bodies.

One of the objects of this invention is to provide a wrench which is equally efficient as a nut wrench and as a pipe wrench;

Another object is to provide an improved 20 wrench which automatically tightens its grip commensurately with the power applied and the resistance offered;

Another object is to provide a wrench which has a wider range of adjustment than 25 an ordinary wrench of substantially equal size;

Another object is to perform all of the functions of a ratchet.

Another object is to provide a wrench in 30 which the jaws remain approximately parallel in every adjusted position;

Another object is to provide a wrench of this character which is convenient to manipulate for opening and closing;

35 Another object is to provide a wrench of this character which is strong, durable and compact; and—

Another object is to provide a wrench of this character which is composed of few and 40 simple parts and may be manufactured at a comparatively slight cost.

Other objects and advantages may become 45 apparent to persons who read the following details of description in connection with the accompanying drawings, in which:

Figure 1 is a side elevation of my improved wrench;

Fig. 2 is a similar view, except that one 50 of the connecting plates or links is removable.

Fig. 3 is a top plan view of the wrench.

Fig. 4 is a view disclosing a portion of the wrench having the jaws in a partially closed

position and in engagement with a cylindrical object; and—

Fig. 5 is a transverse sectional view along the line 5—5 of Fig. 2.

Referring to the drawings in detail in which similar reference characters correspond with similar parts throughout the several views, the wrench consists of separable members or elements 6, 7, 8, 9, 10, 11 and 12. The element 6 constitutes the major element and consists of a handle 13, a jaw 14 and a cam 15, this member being apertured at the 65 base of the cam 15, as indicated at 16.

The minor element 7 consists of a jaw 17, a manipulative element or thumb-piece 18 and a convexed element or abutment 19. The cam 15 terminates in a concaved portion 70 which receives the abutment 19 and constitutes a complementary abutment which co-operates with the pin, stud or abutment 10 for limiting movement of the major and minor members with relation to one another, 75 as will hereinafter become apparent.

Each of the plates or links 8 and 9 has a slot or aperture 20 therethrough, and the studs or ends of pin 10 extend through the apertures 20 and abut against the plates at 80 the upper ends of these apertures so as to limit movement of the member 7 with relation to the links 8 and 9, and it will be seen that the pin 10 thus co-operates with the abutment 19 for limiting movement of the 85 member 7, while keeping the latter constantly parallel with the jaws 14. However, when the member 7 approaches the jaw 14 while the abutment 19 slides along the cam 15, the points or free ends of the jaws move 90 toward one another somewhat faster than the remaining portions of jaws move and, therefore, although the jaws remain in an approximately parallel relation, they converge somewhat toward their free ends, 95 thereby providing the maximum holding efficiency.

In order that the maximum convenience may be obtained in opening and closing the jaws, I provide one or both of the plates 8 100 and 9 with manipulative elements 21 and 22. The manipulative element 21 projects beyond the manipulative element 18 in the direction of the free end of the jaw 17, thereby providing a very convenient means for 105 swinging the plates backward by means of a

thumb, or finger until the cam 15 has raised the manipulative element 18 sufficiently to become operative for completing the rearward movement, that is, the movement whereby the jaws are opened. The manipulative element 22 is also convenient for opening the jaws; this element being disposed conveniently for operation by a thumb or finger when using.

10 The plates 8 and 9, being relatively broad, serve to hold the members 6 and 7 in proper alinement with one another.

Although I have described this embodiment of my invention very specifically, it is not intended to limit my invention to these exact details of construction and arrangement of parts, but I may make minor changes within the scope of the inventive idea disclosed in the foregoing description and appended claims.

What I claim as my invention is:

1. A wrench comprising a major member having a jaw, a minor member having a jaw, a pair of links pivotally secured to said major member and having a separate pivotal connection with said minor member for holding them in co-operative relation for engaging an object to be turned, and oppositely extending studs on said minor member adapted to move against one of said links so as to limit movement of said minor member with relation to said links.

2. In a wrench, a major member consisting of a handle and a jaw and a cam and having an aperture therethrough at the base of said cam, a minor element comprising a jaw and a manipulative element and having an aperture therethrough, a pair of apertured links, and pivots extending through said links and through the aper-

tures of said major and minor members to movably secure these members together in such relation that a part of said minor member can move on said cam when said manipulative element is properly manipulated, 45 said cam being of the proper shape to keep the jaw of said minor member approximately parallel with the jaw of said major member in each of the working positions of the jaws.

3. In a wrench, a major member consisting of a handle and a jaw and a cam and having an aperture therethrough at the base of said cam, a minor element comprising a jaw and a manipulative element and having 55 an aperture therethrough, a pair of apertured links, provided with a manipulative element and pivots extending through said links and through the apertures of said major and minor members to movably secure 60 these members in such relation that a part of said minor member can move on said cam when the first said manipulative element is properly manipulated; said cam being of the proper shape to keep the jaw of 65 said minor member approximately parallel with the jaw of said major member in each of the working positions of the jaws, the manipulative element of said links being operable to move the first said manipulative 70 element into position for its effective manipulation.

In testimony whereof I have hereunto set my hand in the presence of two subscribing witnesses.

ANDREW SPORUP.
